UNITED STATES PATENT OFFICE.

GAYLARD W. DENYES AND OWEN SCHUTT, OF CASSOPOLIS, MICHIGAN.

DESIGN FOR A SHOE FOR GRAIN-DRILLS.

SPECIFICATION forming part of Design No. 32,295, dated February 27, 1900.

Application filed January 31, 1900. Serial No. 3,373. Term of patent 14 years.

To all whom it may concern:

Be it known that we, GAYLARD W. DENYES and OWEN SCHUTT, citizens of the United States, residing at Cassopolis, in the county 5 of Cass and State of Michigan, have invented and produced a new and original Design for Shoes for Grain-Drills, of which the following is a specification, reference being had to the accompanying drawings, forming part thereof.

- 10 Figure 1 is a perspective view of a grain-drill shoe, showing our new design; and Fig. 2, an inverted plan view of the same.

As shown in the drawings, the leading or material feature of our design consists of the 15 diverging and outwardly-curved rear angle or "heel" of the shoe, the sides being vertical and in contact at the forward part, diverging both rearwardly and downwardly at the rear lower portion, as shown.

- 20 A is a vertical tapering tube having a for-

ward extension A', having rearwardly-diverging sides and a concave upper line.

B is the parallel vertical forward part of the shoe, which extends backward and in diverging outwardly-curved faces at each side 25 of the part A' and having the lower rear portions oppositely curved and diverging both rearwardly and downwardly, as at C.

Having thus fully described our invention, what we claim as new, and desire to secure 30 by Letters Patent, is—

The design for a grain-drill shoe, as herein shown and described.

In testimony whereof we affix our signatures in presence of two witnesses.

GAYLARD W. DENYES.
OWEN SCHUTT.
